OXYGEN DELIVERING APPARATUS OF THE
DEMAND TYPEJay A. Heidbrink, Minneapolis, Minn., assignor to
Air Reduction Company, Incorporated, New
York, N. Y., a corporation of New York

Application April 10, 1941, Serial No. 387,936

9 Claims. (Cl. 128—203)

My invention relates to oxygen delivering apparatus of the demand type and has for its object to provide apparatus to be worn by pilots, aviators and others at altitudes so high that it is necessary to supply added oxygen to such wearers.

It has been common practice to provide in conjunction with a mask worn by such persons, means including a rebreathing compartment and tube connections thereto for delivering to the breathing line a constant stream of oxygen and for adding to said stream at inhalation a certain percentage of external air, exhalations going first to refill the rebreathing compartment and then escaping to atmosphere.

It has been found that at great heights and in the severe cold which is there encountered it may be undesirable to inhale external air for the reason that it tends to cool the gases going to the lungs to an excessive degree and to produce freezing of the inlet air valve. Also, where the breather is under surrounding conditions of abnormal barometric pressure or where those conditions change rapidly as in the rapid ascent or descent of an airplane, exclusion of nitrogen from the lungs will prevent pathological disturbances which sometimes result in what is known as the bends. For these reasons under certain conditions it has been found advantageous to provide means whereby inhalation draws in oxygen only, exhalation taking place as before, first to refill the rebreathing compartment and then to discharge to atmosphere the last of exhaled gases, which are those most heavily charged with carbon dioxide. And for carrying out this latter method I have discovered that better results are obtained by having intermittent delivery of the oxygen upon inhalation only and of a volume sufficient to meet any demand of the person so inhaling, that is, to supply oxygen as demanded by the inhalation capacity of the individual wearing the apparatus.

It is, therefore, a principal object of my invention to provide apparatus having an inhalation circuit closed to external air in combination with a rebreathing compartment and means associated with the rebreathing compartment whereby when the same is emptied by the early part of an inhalation, valve mechanism will operate to permit inlet of oxygen to complete the full respiration.

It is a further object of my invention to provide a special type of rebreathing and reservoir compartment which embodies a metal casing and a folded flexible sheet sealed within said metal cas-

ing, which upon exhalation will move to the top of the compartment, expanding it to full capacity for holding a maximum volume of exhaled gases and which upon inhalation will move in the opposite direction under atmospheric pressure and will actuate the long arm of a two-armed lever, thereby opening the oxygen valve until the demands of the wearer for a full inhalation are satisfied by resulting inflow of oxygen.

It is a further object of my invention to provide means for supporting the aforesaid rebreathing compartment under the coat of the aviator where it will not be subject to severe external cold and to conduct the oxygen to the metal casing rebreathing compartment under said coat.

It is a further object of my invention to provide protected exhaling valve means which may be positioned adjacent the metallic casing of the rebreathing compartment under the coat of the aviator so that exhalation will at all times be free from danger of freezing.

It is a further object of my invention to make the exhaling valve of a nature such that even if worn externally of the coat it will none the less keep itself heated to a degree which will prevent freezing.

The full objects and advantages of my invention will appear in connection with the detailed description thereof and the novel features by which those advantages are secured will be particularly pointed out in the claims.

In the drawings:

Fig. 1 illustrates the oxygen supplying apparatus as worn, viewed from the side.

Fig. 2 is a plan view of that part of the oxygen delivering apparatus which is worn under the coat with some parts broken off.

Fig. 3 is an end view of a part of the apparatus taken on line 3—3 of Fig. 2.

Fig. 4 is an enlarged sectional view taken on line 4—4 of Fig. 3 as the apparatus is positioned when beneath the coat of the wearer.

Fig. 5 is an enlarged sectional plan view taken through the oxygen valve mechanism and a part of the rebreathing compartment along the line indicated at 5—5 of Fig. 6.

Figs. 6, 7 and 8 are transverse sectional views of the rebreathing compartment and parts of the valve mechanism taken on line 6—6 of Fig. 2, with the rubber sheet in different positions due to exhalation and inhalation respectively.

Fig. 9 is a sectional view showing the mask connector T and the means of attachment of

the exhaling valve when the same is external to the coat of the wearer.

Referring to Fig. 1, a mask 10 of suitable construction is secured by means of a band 11 upon the face of the wearer. This mask is provided with a turret 12 in which is located a microphone (not shown), said microphone being directly in front of the mouth of the wearer. The mask is provided with a tube 13 which extends from the lower center of the mask body at an outward angle, as shown in Fig. 1. This tube has applied thereto a connector member 14 which is shown in detail in Fig. 9. It comprises a connector tube 15 held within outlet tube 13 and extension tubes 16 and 17 at right angles thereto in the form of a T, which receives the ends 18 and 19 of two extension tubes 20 and 21. These tubes will preferably be corrugated, as shown, although uncorrugated or smooth tubes may under certain conditions be employed. The union member 14 also is provided with a threaded opening 22, Fig. 9, which may receive the exhaling valve 23 as shown in Fig. 9 or may be closed with a cap 24, as indicated in Fig. 1, when it is desirable to have the exhaling valve positioned under the coat of a wearer.

As best shown in Figs. 2, 4 and 5, the re-breathing compartment comprises a metal casting 24 circular in cross section provided with a bottom 25, cylindrical wall 26 and a perforated cover 27, the perforations being a series of round openings 28, as clearly shown in Fig. 2. As shown in Fig. 4, the cover 27 is provided with a flange 29 which grips between it and the cylindrical wall 26 the edge 30 of a sheet of flexible rubber 31. This sheet of rubber is folded upon itself as indicated at 32, Fig. 4, and has a portion 33 of its body engaging a flat disc lever 34 which is secured to a bar 35, Figs. 6, 7 and 8. The bar 35 has an upstanding arm 36 mounted on a pintle 37 pivoted in ears 38, 39 on the angle posts 40, 41 which are secured by screws 42, 43 upon the body of the cylindrical wall 26. The screws 42, 43 extend through into a circular casting 44 and hold it upon wall 26 over an annular gasket 45.

The wall 26 is provided with a circular opening 46, Fig. 4. About this opening is secured a casting 47 by means of screws 48, as shown in Figs. 4 and 8. The casting has therein a tubular opening 49 which leads into a central opening 50 extending through a tubular extension 51 of the casting 47, these parts preferably being of Bakelite, as indicated. Extension 51 has formed on its top a Bakelite cap 52 which has an annular flange 53 adapted to surround the tube 51 over a gasket 54 at the end of tube 51, and to be held in position by a post 55 screwed into casting 47 at 56 and threaded at 57 into an extension nut 58 fast on cap 52. A thumb piece 59 enables the parts to be brought into rigid gas-tight relation.

As shown in Fig. 3, the cap 52 is provided with opposite extensions 60 and 61 each having an annular rib 62 for receiving the ends 63 and 64 of tubes 20 and 21. These tubes are thus readily attached and detached from the extensions 60 and 61. These wing extensions open through cap 52 into chamber 50, as indicated at 65 in Fig. 4.

By these means, as will be apparent from the drawings and the foregoing description, the re-breathing compartment 66 within the casing 24 is put in free communication with the mask and the passages leading therefrom.

The exhaling valve, indicated in Fig. 9 as positioned externally upon the union member 14, may be conveniently attached to the extension 51 directly opposite the opening 46 from re-breathing compartment 66, as shown in Fig. 4. This figure illustrates that a base member of Bakelite 67' on castings 67 has a boss 68 thereon threaded into a boss 69 on the member 47. The boss 68 has an internal chamber 70 (Fig. 4) in communication with the chamber 50 within tubular extension 51. The chamber 70 has formed thereon a valve rim or edge 71 which has held in engagement therewith a valve disc 72 by means of a spring 73 surrounding a fixed post 74 having thereon a pin 75 on which the valve disc 72 is adapted to move back and forth.

Openings 71 communicate past valve disc 72 with chamber 70 for permitting exhalation to pass after the re-breathing compartment 66 has been filled and sufficient pressure is built up to overcome the force of spring 73 engaging valve disc 72. The parts are held assembled in position by means of a cap 78 (Fig. 4) threaded on to the end of tubular casting 67. Surrounding the Bakelite casting 67 is a heavy cap member 79 which is threaded upon the casting 67, as clearly shown in Fig. 4, leaving an annular chamber or space 80 between the inner cylindrical wall of the cap and the outer cylindrical wall of casting 67. The annular chamber 80 opens into a flat cylindrical chamber 81, over cap 78 and communicates with an opening 82 through which the gases of exhalation may pass. It will be understood that valve structure 23 is identically the same in Fig. 9 as in Fig. 4, the parts being differently sectioned in the latter figure.

Oxygen is supplied from a tank with suitable pressure regulator means (not shown) through a tube 83 which, as shown in Fig. 5, surrounds a nipple 84 leading to a valve chamber 85. Valve chamber 85 is formed within a pair of casting members 86 and 87 screwed together at 88 upon a gasket 89 forming an air-tight seal. The member 87 is in turn threaded at 90 into the casting block 44 with a sealing gasket 91 between portions of member 87 and block 44. A guide 92 for valve stem 93 is secured in position by means of a nut 94 threaded into the piece 87. The nut 94 is provided with a valve seat 95, and passages 96 surround the stem 93. Upon the stem 93 is a valve disc 97 which is urged against the valve seat 95 by a spring 98 within the valve chamber 85, thus normally sealing that chamber 85 against passage of gas through air passages 96 into the re-breathing compartment 66.

It will be noted from Figs. 5 and 8 that the short arm 36 of lever 35 has thereon a ball 99 which engages the face of end 100 of valve pin 93. The actual thrust lever arm of this lever system is therefore the distance between the axial center of pin 37 and the point of contact of ball 99.

The container 24 is formed at its bottom with a depression 101 (Fig. 4) carrying a tubular member 102 which is sealed into the cylindrical wall 26. The member 102 is closed by a rubber cap 103. This is a container for condensate from the breath, and the operator can from time to time withdraw the rubber cap 103 to let the accumulated moisture run out. In practice I may carry a rubber band 104, Figs. 2 and 4, about the tubular member 102 and across the top of cover member 27 and about the tube extension 51, as indicated at 105 in Fig. 4, which

would have the effect of aiding in holding the cover 27 in position.

The rebreathing assemblage is supported by a strap 106 which, as indicated in dotted lines in Fig. 1, passes over the shoulders of the wearer and back of his neck under the coat to hold the rebreathing and demand valve mechanism in position.

In practice the overcoat indicated at 107 will be provided with a circular opening 108 through which the tube member 51 will extend while the apparatus is being worn. The tubes 20 and 21 will extend normally, as indicated in Fig. 1, to the mask structure as worn and the assemblage will be held in position for use.

The operation of the valve mechanism to meet the demands of the wearer will readily be understood from Figs. 6, 7 and 8. Upon exhalation, compartment 66 will first become filled with the first part of exhalation, which is the part most richly charged with oxygen and the flexible member 31 will be caused to move to approximately the position indicated in Fig. 8, in which substantially the whole of compartment 66 is filled with gases of exhalation, the gases entering compartment 66 through the opening 46. After the chamber 66 has become filled, as indicated in Fig. 8, and pressure built up to overcome the force of the spring 73 in the exhaling valve, that will open permitting the remainder of the exhalation which contains the larger proportion of carbon dioxide to escape to atmosphere. This operation will take place in the same way whether the exhaling valve 23 is outside the coat, at a distance from the rebreathing compartment, as indicated in Fig. 9, or is within the coat immediately adjacent the rebreathing compartment, as in Fig. 4.

Upon inhalation the rebreathing compartment 66 will first be substantially emptied until, as indicated in Fig. 6, the front flap 33 of the flexible closure 31 will have been brought into engagement with the face of disc 34 forming part of long lever arm 35. Continued inspiration will cause the flexible container to further expand under pressure of external atmosphere with the result that the long lever arm is rocked to the position of Fig. 7 and the valve disc 97 is pushed out against the pressure of spring 98 to open the valve and permit oxygen to move through and around the outer portions of flexible container 31 to opening 46, whence it passes to the lungs of the breather in a volume sufficient to meet the demands of a complete normal inspiration.

This cycle will be repeated continuously in natural breathing, whereby the aviator, observer or other occupant of the plane at high altitudes will be constantly breathing an atmosphere of pure oxygen, only diluted to some extent by water vapor and carbon dioxide, the latter acting in a well-known way to stimulate breathing. The oxygen passing into the rebreathing compartment which is under the heavy coat and next to clothing toward the body of the wearer will be to a considerable extent warmed not only because of the protection and body heat of the wearer, but also because the walls of rebreathing compartment 66 and the flexible member 31 will all be warmed by the warm exhalation which has been passed from the lungs of the wearer into the rebreathing and reservoir compartment.

It is also true that the exhaling valve structure heretofore described will not only receive the warm exhalation of the wearer but this will

be caused to surround the body of the valve toward the point of escape of exhalation gases to atmosphere and thus keep that body warm so that there will be little or no chance of freezing. And in either the position of Fig. 9 or the position of Fig. 4 any condensation in the exhaling valve will readily escape, in the arrangement in Fig. 9 directly to atmosphere, in the arrangement of Fig. 4 back into the passages 70, 49 and through the opening 46 to the drip collector 102.

These are the advantages of this invention which are very obvious from the description and mode of operation outlined above. It may be noted that the double anchorage formed by the tubes 20, 21 between the mask 10 and the tubular extension 51 extending through the coat at 108 will aid in preventing any lift of the mask during rapid descent such as takes place with dive bombing, since the extension 51 extending through the opening 108 in the coat cannot yield and the tubes 20 and 21 will not be readily torn loose.

A further advantage of my invention is to be found in its adaptability to be employed in connection with a fully closed breathing circuit. For this purpose a soda lime container of known form and well understood use (not shown) may be applied in the connection 47 between the casting wall 26 and the tube 50, and the exhaling valve may be entirely cut out so that breathing will pass through the soda lime container either on the inhaling breath alone or on both inhaling and exhaling, all in a well-known manner. By these means the combined expansible reservoir rebreathing compartment and the demand type oxygen inlet valve mechanism may be employed in connection with completely closed circuit administration of oxygen.

40 I claim:

1. A device for administering oxygen and excluding nitrogen comprising a mask, a rebreathing compartment having gas-flow connection with the mask, said compartment comprising a rigid shell having parallel face walls, a perforate cover and a flexible sheet held gas-tight upon the edges of the shell by the cover said sheet being folded upon itself, so that on exhalation it will contact one of said face walls and upon inhalation it will substantially contact the other of said face walls, said connection between the mask and the rebreathing compartment opening from the latter below said flexible sheet.

2. A device for administering oxygen and excluding nitrogen comprising a mask, a rebreathing compartment having gas flow connection with the mask, said compartment comprising a rigid shell having parallel face walls, a perforate cover and a flexible sheet held gas-tight upon the edges of the shell by the cover said sheet being folded upon itself, so that on exhalation it will contact one of said face walls and upon inhalation will be moved by external air pressure to contact the other of said walls, an oxygen valve, and means within said compartment subject to the action of said flexible sheet when the compartment is emptied by an inhalation to effect operation of the valve to permit flow of oxygen into and from the rebreathing compartment as long as inhalation continues.

3. A device for administering oxygen and excluding nitrogen comprising a mask, a rebreathing compartment having gas-flow connection with the mask, said compartment comprising a rigid shell, a perforate cover and a flexible sheet

held gas-tight upon the edges of the shell by the cover, said flexible sheet being folded upon itself so that the same may be pushed against the perforate cover when the rebreathing compartment is filled with exhalation gas and may move toward contact with the bottom of the compartment upon inhalation, an oxygen control valve, and means actuated by the last stated movement of said flexible sheet for operating the valve to permit flow of oxygen into and from the rebreathing compartment as long as inhalation continues.

4. In a device for administering oxygen at high altitudes, a rebreathing compartment comprising a rigid shell, a perforate cover, a flexible sheet removably sealed within the shell by the perforate cover, said flexible sheet being folded upon itself so that the same may be pushed against the perforate cover by exhalation and will be caused to move toward contact with the bottom of the compartment upon inhalation, a tubular connector member secured to a side of the shell and opening therewith beneath the flexible sheet, said connector being adapted to pass through an opening in the coat of a wearer, a mask and tubes adapted to extend outside the clothing from the connector to said mask.

5. In a device for administering oxygen at high altitudes, a rebreathing compartment comprising a rigid shell, a perforate cover, a flexible sheet removably sealed within the shell by the flexible cover, a tubular connector member secured to a side of the shell and opening therewith beneath the flexible sheet, said connector being adapted to pass through an opening in the coat of the wearer, a mask, a tube adapted to extend outside the clothing from the connector to said mask, and an exhaling valve secured adjacent the inner end of the tube and adapted to be positioned with the rebreathing compartment under the coat of the wearer.

6. In a device for administering oxygen at high altitudes, an exhaling valve comprising a casing formed with an inner valve chamber, a valve inside the chamber adapted to open upon exhalation, a second casing member surrounding the casing forming the valve chamber to leave a second chamber around and at the top of said valve chamber casing, said second chamber opening to atmosphere adjacent its top, and openings from the valve chamber into the second chamber, whereby the valve chamber will be maintained warm by exhalation passing around the same and freezing of the valve will be prevented.

7. A device for administering oxygen and ex-

cluding nitrogen comprising a rebreathing compartment formed of a rigid shell having parallel face walls, a flexible sheet folded upon itself and held gas-tight about its edges adjacent one of said walls, said sheet being folded upon itself so that on exhalation it will contact one of said face walls and upon inhalation will be moved by external air pressure to contact the other of said face walls, a lever arm located in said compartment having a flat paddle-like disc adapted to be engaged by said flexible sheet when the same is moved by atmospheric pressure when the compartment is emptied by an inhalation, and a normally closed valve operated by said movement when the rebreathing compartment is substantially emptied to permit flow of oxygen into and from the rebreathing compartment as long as inhalation continues.

8. A device for administering oxygen at high altitudes comprising a rebreathing compartment formed of a rigid shell having parallel face walls spaced apart a distance which will permit the rebreathing compartment to be worn beneath the coat of a wearer, a flexible sheet held gas-tight about its edges adjacent the outer of said walls as worn, said sheet being folded upon itself so that on exhalation it will contact one of said face walls and upon inhalation will be moved by external air pressure to contact the other of said face walls, a tubular connector member secured to an edge wall of the shell and opening therewith between said face walls and at the inside of the flexible sheet and extending at right angles to said face walls, said connector being adapted to pass through an opening in the coat of a wearer, a mask and a tube connected therewith and with the tubular member and adapted to extend outside the clothing.

9. A device for administering oxygen and excluding nitrogen, comprising a rigid casing having parallel walls spaced close together to form a shallow laterally expanded chamber adapted to be positioned under an aviator's coat, flexible means within the chamber subject to external air pressure forming a sealed reservoir, a mask and a breathing line opening into the reservoir including a rigid connector member extending at right angles to the walls of the casing and adapted to pass through an opening in the aviator's coat, and means for supplying oxygen to the reservoir including valve mechanism therein actuated by movements of the flexible means resulting from respiration.

JAY A. HEIDBRINK.
